UNITED STATES PATENT OFFICE.

TRAUGOTT F. KELLER, OF BROOKLYN, NEW YORK, ASSIGNOR TO THE CLEMENTS COMPANY, A CORPORATION OF NEW YORK.

BOLT-ANCHOR.

1,116,710.

Specification of Letters Patent. Patented Nov. 10, 1914.

Application filed June 21, 1913. Serial No. 774,992.

To all whom it may concern:

Be it known that I, TRAUGOTT F. KELLER, a citizen of the United States, and a resident of Brooklyn, in the county of Kings and State of New York, have invented certain new and useful Improvements in Bolt Anchors, of which the following is a specification, reference being had to the accompanying drawings, forming a part thereof.

10 My invention relates to improvements in bolt anchors and its object is to provide a simple and inexpensive device of this character which shall have advantages over those which hitherto have been known.

15 I will describe my invention in the following specification and point out the novel features thereof in appended claims.

Referring to the drawings,—Figure 1 is a sectional elevation of a wall with a bolt anchor therein which embodies the present invention, together with a bolt in the anchor to illustrate the manner in which it is used. Fig. 2 is a sectional side elevation and Fig. 3 is an end view of the bolt anchor shown in Fig. 1. Fig. 4 is an end elevation of a similar bolt anchor with its exterior constructed with projections.

In Figs. 5 and 6 is shown in sectional side elevation and in transverse section respectively, a modified form of bolt anchor which also embodies my invention, which in this case is made of metal of sufficient softness to enable the bolt which is used with it, to cut its own thread therein.

35 Another modification of construction is shown in Figs. 7 and 8 which are respectively a sectional side elevation and an end view of a bolt anchor which is solid at its inner end.

40 Like characters of reference designate corresponding parts in all the figures.

Bolt anchors constructed according to my invention comprise a cylindrical shell 10 within which is a tapered bore converging 45 toward the inner end of the shell. In the forms shown in all of the figures except 5 and 6 this tapered bore is provided with screw-threads 11. A longitudinal cut or slit 12 is made through the shell into the bore of the shell which extends from the outer end of the shell back through the greater part of its length. The outside of the shell is substantially cylindrical but it may be cut away as at 18 near the inner end

of the slit 12 to make it more flexible at 55 this part. If desired it may be provided with projecting lugs such as those shown at 13 in Fig. 4. When the shell is made of soft metal, it is not necessary to have it internally threaded because the bolt which is 60 used with it may cut its own threads in the shell. To facilitate this, the tapered bore may be fluted or provided with internally projecting longitudinal ribs. Such a shell is shown in Figs. 5 and 6 in which it is designated by 10^A and the ribs by 14.

The shell 10^B shown in Figs. 7 and 8 is similar to that shown in Fig. 2 but its inner end 15 is solid. This shell is shown with two slits 12—12 and it is obvious that one 70 or any desired number of these slits may be provided in either this or any of the other forms.

Referring now to Fig. 1, I will describe the manner in which this device is used. In 75 a wall, floor or other structure 20, a hole 21 is drilled of sufficient size to permit the insertion of the bolt anchor. Then a bolt 22 is screwed into the tapered thread 12. This causes an expansion of the shell at the outer 80 or slotted end as is clearly illustrated in this Fig. 1. The outer surface of the shell is thus forced snugly against the bore of the hole 21 and effectively prevents the withdrawal of the anchor as long as the bolt remains in 85 place. If the structure in which the bolt anchor is used is of certain materials, it is desirable to provide the exterior of the shell with the projections 13 in order to increase its holding effect. By slotting the anchor 90 from the outer end, immediate expansion will occur as the bolt enters the anchor. This initial expansion is of great advantage and is accomplished by the bolt engaging the anchor at the outer end. It is also facilitated by the weakening of the wall as at 18 in Fig. 1.

The arrangement of my invention is particularly valuable when the bolt cuts its own threads in the anchor and furthermore permits the use of bolts of varying lengths. Another advantage arises from the fact that where a bolt has been used and an anchorage secured, and thereafter it is desired to remove the bolt, another bolt may be used and 100 a new anchorage secured.

I have illustrated several forms of my invention to show that I do not limit myself

to any specific construction, as many structural modifications may be made within the spirit of my invention and the limitations of the claims.

5. What I claim is:

1. A bolt anchor comprising a cylindrical shell adapted to receive an expansion screw and having a tapered hole from the outer end extending through the shell and converging toward the inner end thereof, said shell being slotted longitudinally from its outer end through the greater part of its length.

15. A bolt anchor comprising a cylindrical shell of metal annularly continuous at its inner end having a tapered threaded hole from the outer end converging toward the inner end thereof, said shell being slotted longitudinally from its outer end.

20. 3. A bolt anchor comprising a cylindrical shell of metal annularly continuous at its inner end having a tapered threaded hole from the outer end extending through the shell and converging toward the inner end thereof, said shell being slotted longitudinally from its outer end.

nally from its outer end through the greater part of its length.

4. A bolt anchor comprising a shell having a tapered bore converging toward the inner end of the shell, said shell being slotted 30 from its outer end through the greater part of its length and being cut away near the inner end of the slit.

5. A bolt anchor comprising a cylindrical shell of hard metal annularly continuous at 35 its inner end, having a tapered threaded hole from its outer end extending through the shell and converging toward the inner end thereof, said shell being slotted longitudinally from its outer end through the greater 40 part of its length and being provided with an annular groove near the inner end of the slit.

In witness whereof, I have hereunto set my hand this 19th day of June, 1913.

TRAUGOTT F. KELLER.
